ATTORNEY.

UNITED STATES PATENT OFFICE

110,195

DESIGN FOR A PORTABLE LAMP

Isidore Scheinberg, Baltimore, Md.

Application July 7, 1937, Serial No. 70,289

Term of patent 3½ years

To all whom it may concern:

Be it known that Isidore Scheinberg, a citizen of the United States of America and a resident of the city of Baltimore, State of Maryland, has invented a new, original, and ornamental Design for a Portable Lamp, of which the following is a specification, reference being had to the accompanying drawing, forming part thereof.

The figure is a side elevational view of a portable lamp, showing my new design.

I claim:

The ornamental design for a portable lamp, as shown.

ISIDORE SCHEINBERG.
